(57) **CLAIM**

The ornamental design for a tool-box, as shown and
described.

DESCRIPTION

FIG. 1 is a perspective view of a tool-box, showing my new
design;

FIG. 2 is another perspective view thereof;

FIG. 3 is a front view thereof;

FIG. 4 is a top view thereof;

FIG. 5 is a bottom view thereof;

FIG. 6 is a right side view thereof;

FIG. 7 is a left side view thereof; and,

FIG. 8 is rear view thereof.

The dash-double-dot lines in the drawings represent tangent
points of a radius edge. The breakaway portions shown in
FIGS. 1-5 are included to show that the tool-box has no
specific length. Shading in the figures are for illustrative
purposes only and form no part of the claimed design.
